(57) **CLAIM**

The ornamental design for a cutting board for dividing a bread loaf, as shown and described.

DESCRIPTION

FIG. 1 is a top plan view of a cutting board for dividing a bread loaf embodying my new design, the bottom plan view being a mirror image thereof;
 FIG. 2 is a front elevational view; the rear elevational view being a mirror image thereof;
 FIG. 3 is a left elevational view; the right elevational view being a mirror image thereof; and,
 FIG. 4 is a perspective view of the cutting board for dividing a bread loaf embodying my new design.
